UNITED STATES PATENT OFFICE

159,281

TABLE LIGHTER

Sylvester G. Lipic and Walter E. Moore, St. Louis
County, Mo., assignors to Ritepoint Co., St.
Louis, Mo., a corporation of Missouri

Application August 25, 1949, Serial No. 4,696

Term of patent 14 years

(Cl. D48—27)

To all whom it may concern:

Be it known that Sylvester G. Lipic and Walter E. Moore, both citizens of the United States, and residents of the county of St. Louis, State of Missouri, have invented a new, original, and ornamental Design for Table Lighter, of which the following is a specification, reference being had to the accompanying drawing, forming a part hereof.

In the drawing:

Fig. 1 is a side elevational view of a table lighter showing our design;

Fig. 2 is a front elevational view; and

Fig. 3 is a top view.

We claim:

The ornamental design for a table lighter, as shown.

SYLVESTER G. LIPIC.
WALTER E. MOORE.
